UNITED STATES PATENT OFFICE.

ELMER S. SMITH, OF BOUND BROOK, NEW JERSEY

CASH-REGISTER.

No. 825,493.

Specification of Letters Patent.

Patented July 10, 1906.

Application filed August 1, 1904. Serial No. 219,025.

To all whom it may concern:

Be it known that I, ELMER S. SMITH, a citizen of the United States, and a resident of Boundbrook, in the county of Somerset and State of New Jersey, have invented certain new and useful Improvements in Cash-Registers, of which the following is a specification.

My present invention has reference to improvements in cash-registers; and the invention relates more particularly to a novel cash-register mechanism in which a set of actuating-keys, preferably in the form of push-buttons or the equivalents thereof, bearing numbers and other symbols, are employed for actuating the recording and registering mechanisms and other devices of the apparatus.

My present invention relates, furthermore, to the application of one or more phonographs or other suitable talking-machines to a cash-register, the same being combined with the mechanism and devices of the cash-register in such a manner that in actuating the mechanisms and devices of the cash-register one or more of such talking-machines are also set in operation to present in imitation of the human voice the amount of each sale, and, if desired, the name or symbol of the clerk who is recording the sale.

The invention has for its principal object to provide a simple and cheaply-constructed cash-register which shall be most efficient and in which the parts of the controlling and the indicating-drum mechanism have been reduced to a minimum, whereby the workings and operations of the several mechanisms and devices are most effective and the parts thereof less liable of getting out of order.

A further object of this invention is to provide, in connection with a cash-register and its mechanism, one or more talking-machines, which are actuated when a purchase or sale is recorded, and thereby presents to the purchaser the amount of such purchase or sale in imitation of the human voice.

A further object of the present invention is to provide a means, preferably in the form of a resetting or charging device, the movement of which acts, first, to close a shutter or slide over the indicating window or opening located in front of the sales-indicating drum or drums; secondly, to wind the motor mechanism, by means of which the mechanism of the talking machine or machines are

set in operation; thirdly, to return the mechanisms and parts of the previously-operated talking machine or machines to their normal initial positions; fourthly, to return the previously-actuated indicating mechanisms and indicating drum or drums to their normal initial positions; fifthly, to release the actuating-keys or push-buttons which have previously been brought into their locked and inactive relation by the actuation of one of a set of keys or push-buttons in each row or bank of such keys or push-buttons; sixthly, to feed a tape in position for printing thereon a record of the purchase or sale or such other matter as may be desired, and, finally, a further object of this invention is to provide an actuating means, preferably in the form of a single push-button or main key, the movement of which acts, first, to remove the said shutter or slide from in front of the indicating drum or drums; secondly, to release and set in position for reproducing the sound-reproducer of the talking machine or machines; thirdly, to lock all the indicating keys or push-buttons upon the keyboard; fourthly, to release a drawer holding or locking mechanism; fifthly, to actuate a printing device, and, sixthly, to bring the parts of a total adding or counting device in its inactive relation with the remaining parts of the apparatus.

In brief, the general operation of the cash-register is as follows: The operator sets the various mechanisms and devices by means of the resetting device or charging-bar. Then he actuates the indicating drum or drums by pressing the proper indicating key or keys to rotate the proper amounts of the purchase or sale in front of the closed window or windows, another bank of keys or push-buttons being also arranged for actuation to operate a total adding or counting device and the initial or symbol device of the clerk, the operator finally operating the single key or push-button, whereby the mechanisms are actuated to expose to view the amount of the purchase or sale to set the talking machine or machines in operation and to throw out the total-adding devices, that those devices will not become actuated during the return movements of the various parts to their normal initial positions when the resetting device or charging-bar is again operated by another clerk desiring to record and register another sale. Other objects of the present invention not

at this time more particularly specified will be clearly understood from the following description of the same.

My invention consists, primarily, in the novel construction of cash-register hereinafter set forth, and, furthermore, this invention consists in the novel features, structures, and the general arrangements and combinations of devices and parts, as well as in the details of the construction of the same, all of which will be more fully described in the accompanying specification and then finally embodied in the clauses of the claim, which are appended to and form an essential part of this specification.

The invention is clearly illustrated in the accompanying drawings, in which—

Fig. 1 is a front view of a cash-register embodying the principles of my invention. Fig. 2 is an end elevation of the same, and Fig. 3 is a side view of the upper portion of the cash-register casing and a trumpet or horn-shaped device connected with said casing for conveying the sounds rendered from the talking machine or machines within the casing. Fig. 4 is a transverse vertical section of the cash-register, said section being taken on line 4-4 in Fig. 1 of the drawings looking in the direction of the arrow *x*; and Fig. 5 is a face view of a striking gong and portions of its striking mechanism. Fig. 6 is a transverse vertical section taken on line 6-6 in said Fig. 1 with one of the said keys or push-buttons in its actuated or depressed position and with the speaking trumpet or horn removed. Fig. 7 is a face view of a front plate of the cash-register in its detached position and a rear view of the various devices and mechanisms which are arranged in their operative positions upon the inner face of said plate looking in the direction of the arrow *y* is said Fig. 4, and Fig. 8 is a detail view of a portion of an arm for setting the drawer-releasing device. Fig. 9 is a face view of the said front plate of the cash-register with the indicating-drums, the counting devices, the talking-machines, and intermediately-arranged actuating mechanisms omitted from the said view. Fig. 10 is a horizontal sectional representation in detail, said section being represented as taken on line 10-10 in Figs. 4 and 7 looking in the direction of the arrow *z* in said Fig. 7; and Fig. 11 is a bottom view of the winding device for winding the spring of the phonograph or other talking-machine motor. Fig. 12 is a face view of the indicator-roll or drum-actuating rack, mechanism for setting the phonograph-recorder, and means for locking the indicator keys or push-buttons in their locked positions, the parts being represented in their normal initial positions and the parts shown being those used in connection with the row or bank of clerk-keys; and Fig. 13 is a similar view of the said devices, illustrating the parts in their actuated positions. Fig.

14 is a detail vertical section, taken on line 14-14 in said Fig. 12 looking in the direction of the arrow *u* in said figure. Fig. 15 is a similar view of the same parts, showing the positions of said parts after the resetting or charging bar has been actuated, and Fig. 16 is a vertical section taken on line 16-16 in Fig. 13 looking in the direction of the arrow *v* in said Fig. 13 and showing the relative positions of the parts after one of the keys or push-buttons has been depressed. Fig. 17 is a face view of an indicator-roll or drum-actuating rack, mechanism for setting the corresponding phonograph-recorder, and means for locking the sales-recording keys or push-buttons, the parts being shown in one of their actuated positions; and Fig. 18 is a vertical section taken on line 18-18 in said Fig. 17 looking in the direction of the arrow *w*. Fig. 19 is a detail face view of a portion of the mechanism represented in Fig. 17, showing in dotted outline a portion of the resetting or charging bar before it is actuated and a locking or holding latch in its normally disengaged relation with a tipping plate of said mechanism indicated in Fig. 17; and Fig. 20 is a similar view of the same parts, showing the locked engagement of the said tipping plate with the said holding-latch after the resetting or charging bar has been actuated. Fig. 21 is a vertical section taken on line 21-21 in Fig. 12, and Fig. 22 is a vertical section taken on line 22-22 in Fig. 13. Figs. 23 and 24 are detail vertical sections, on enlarged scales, of some of the clerk-indicating keys and parts with which they are connected, showing the parts of the said keys respectively in the normal initial and their depressed positions. Fig. 25 is a longitudinal vertical section of the indicator-drums and their respective sleeves, the main shaft on which said parts are arranged being represented in elevation; and Fig. 26 is a cross-section taken on line 26-26 in said Fig. 25 looking in the direction of the arrow *t*. Fig. 27 is a side view of one form of phonograph-motor and a releasing device connected therewith which is actuated by the said resetting or charging bar. Fig. 28 is a top view of the parts shown in Fig. 26; and Fig. 29 is a horizontal section in detail, said section being taken on line 29-29 in Fig. 27. Fig. 30 is a side view of a ticket and pad printing device to be used with the apparatus, the parts being represented in their normal initial positions; and Fig. 31 is a similar view of the said device with the parts thereof shown in their actuated positions. Fig. 32 is a side view of a tape-printing device which may be used with the apparatus in lieu of the device shown in said Fig. 30; and Fig. 33 is a similar view of the said device with the parts thereof shown in their actuated positions.

Similar characters of reference are employed in the above-described views to indicate corresponding parts.

Referring now to the several figures of the drawings, the reference character 1 indicates the exterior shell or casing of the cash-register, the said shell or casing being of any desirable shape and ornamentation and comprising the sides 2, the back 3, the front 4, a base 5, and a top 6, substantially as illustrated. Slidably arranged within the lower part of the said shell or casing 1 is a suitable drawer 7, which is normally locked or held against withdrawal by a locking or holding mechanism, the various parts of which are arranged and constructed substantially in the manner shown in Fig. 4 of the drawings and as will be hereinafter more fully described. It will be noticed from the said Fig. 4 that the shell or casing 1 is preferably made of a greater width in its lower part than in its upper portion, these lower and upper portions of the shell or casing being made with an inclined opening between them, in which I have suitably arranged and secured a front plate 8, upon the back of which most of the mechanisms and devices of the cash-register are arranged and operate.

The upper front portion of the shell or casing 1, as will be seen from an inspection of Fig. 1 of the drawings, is provided with one or more windows or openings 9, back of which the indicator-drums revolve in the manner to be hereinafter more fully described. The front plate 8 is provided with any suitable number of rows of openings, through which the sales-indicating keys or push-buttons 10 project, and the said plate 8 may also be provided with another set of openings, through which a bank of clerk-indicating keys or push-buttons 11 project. The said front plate may be provided also with an opening from which projects a key 12, preferably termed a "no-count" key, which when depressed throws out of operation the general counter or adder, as will hereinafter appear.

Suitably-constructed plates or bars 13 may be secured upon the face-plate along the sides of the key-barrels, in which the keys are movably arranged to prevent tampering with these parts and also to prevent the withdrawal of certain connecting-pins by means of which each key is operatively connected with its key-barrel. Slidably arranged upon the outer surface of the said face-plate 8 between a pair of suitable guides, as 14, is a resetting or charging bar 15, which is provided with a finger-piece 16 of any desired shape and has its upper end portion 17 extending beneath the cut-away part 19 of the lower marginal edge 18 of the upper part 4 of the casing, as clearly illustrated in Figs. 1 and 4. The upper portion 20 of the said face-plate 8, as will be seen from an inspection of Figs. 4 and 6, extends into and terminates within the inner upper part of the shell or casing 1,

and it is provided with a slot or opening 21 and a pair of larger openings 22, into which portions of the indicator-drums extend.

Referring now to Figs. 7 and 25, it will be seen that there is an arrangement of five independently revolving indicator-drums 70 which are respectively indicated by the reference characters 24, 25, 26, 27, and 28; but of course it will be understood that this is but one arrangement of such drums, and I may employ a larger or smaller number of such drums, according to the size and kind of cash-register. Thus in the present instance the drum 24 is for the purpose of indicating the digits or cents from "1" to "9," inclusive, the drum 25 indicating the tens of cents, the drum 26 indicating the dollars from "1" to "9," inclusive, the drum 27 bearing the dollar-symbol, and the drum 28 being the clerk initials or other insignia. That each drum may have an independent rotary motion the drum 24 is secured directly upon a main shaft 29, which is provided at one end with a printing wheel or disk 30. Suitably secured upon the said shaft 29 and operatively connected with the side of the drum 24 is a pinion 31. Slipped over the said shaft 29 and arranged between the said printing-wheel or disk 30 and a collar 32 is a tube 33, upon which the drum 25 is secured, said tube 33 being provided at its opposite end with a printing wheel or disk 34. Suitably secured upon the said tube 33 and operatively connected with the side of the drum 25 is a pinion 35. Slipped over the said tube 33 and arranged between the printing wheel or disk 34 and a collar 36 is a pinion 38 being also secured upon said tube and being operatively connected with the side of the said drum 27. A printing wheel or disk 39 is also secured upon said tube 37. Slipped upon the said tube 37 and arranged between the said printing wheel or disk 39 and a collar 40 upon said tube 37 is a tube 41, upon which the indicator-drum 28 is arranged and secured, a pinion 42 being also secured upon said tube 37 in operative engagement with the side of said drum 28. The said tube 41 is provided upon its opposite end with a printing wheel or disk 43. The several printing wheels or disks above mentioned are for printing the amounts and clerk-initials upon suitably-disposed tape-rolls. (Not shown herein.) When these several parts have been assembled in their operative relations, (indicated more particularly in said Figs. 7 and 25,) they are arranged in suitable bearings 44, which are suitably secured upon the inner face of the face-plate 8. Spiral springs 45, having their outer ends secured to said plate 8 and having their inner ends respectively secured to the shaft 29 and the respective tubes 33, 37, and 44, may also

be employed for the purposes of helping to return the actuated parts to their normal initial positions, as will presently appear.

Referring again to the resetting or charging bar 15, the portion 17 of the said bar has connected therewith a rearwardly-extending and preferably cube-shaped extension 46, which is slidably arranged in the previously-mentioned slot or opening 21 of the plate 8 and acts as a guide for the proper reciprocatory movements of the said bar 15. Slidably connected with the said extension 46 and extending downwardly within the shell or casting 1 is a bar 47, which is made with a grooved or channeled part 48, as clearly indicated in dotted outline in Fig. 4 of the drawings. In the upper portion of said grooved or channeled part 48 is a block 49, provided with a A-shaped or other angular depression or notch 50, and in the lower portion of said groove or channeled part 48 is a second block 51, having an inclined surface 52. Located back of the said face-plate 8 and suitably secured to said plate 8 by means of studs or posts 53 or in any other suitable manner is a guide-plate 54, which is provided with an opening or slot 55 and a number of other openings or slots 56, said openings or slots providing suitable guides for the purposes to be presently set forth. Suitably secured to the lower end portion of the bar 47 by means of a connecting-piece 57, which is movably arranged in the said opening or slot 55, is a lower and laterally-extending cross-bar 58, upon which are arranged a number of upwardly-extending fingers or posts 59, each of which is provided with an angular or rounded marginal edge 60. The said guide-plate 54 is made also with a suitable number of openings 61 and with a number of studs 62, each stud 62 being provided with a spring-controlled catch-arm 63 and a pin 64, extending through such opening 61 in the plate 54 and in contact with the lower surface of the cross-bar 58, substantially as illustrated in Figs. 9, 17, 18, 19, and 20, the said catch-arms 63 being moved upwardly by the action of their springs 65 when the cross-bar 58 moves in an upward direction away from the openings 61, but the pins 64 in said openings 61 limiting the pivotal movements of said catch-arms 63, substantially as and for the purposes hereinafter more particularly specified.

Arranged directly against the inner surface of the face-plate 8 and capable of a slight vertical movement are a number of holding-plates 66, according to the number of banks of recording-keys used with the cash-register. Each plate 66 is provided at its upper end with a right-angled projection or shoulder 67, having an opening which is in alignment with a vertically-arranged slot 68 in the main body of the plate and with a smaller right-angled projection or lug 69,

which under normal conditions rests upon the upper edge of a hinged tipping plate 70, as illustrated in Fig. 12 of the drawings. The number of such tipping plates 70 may be varied according to the number of holding-plates 66 and the number of banks of keys employed. Now referring to Figs. 12, 13, and 17 it will be seen that each plate 70 is provided along one of its edges with perforated ears or lugs 71, a pivotal pin 72 being used with the said ears or lugs 71 and the one pair of studs 53 for hinging the said plate 70 in position and a suitable spring 73 being employed for forcing the plate 70 in the positions indicated in Figs. 14 and 15, with the upper edge of the plate 70 beneath the projection or lug 69 of the adjacent holding-plate 66. Each tipping plate 70 is also made with an opening or slot 74. Referring now to Fig. 10 of the drawings, it will be seen that there are arranged between the guide-plate 54 and the face-plate 8 and capable of a slideable reciprocal movement in each slot 68 a number of rack-bars 75, the upper end portions of which are provided with gear-teeth 76, which are in mesh with the gear-teeth of the respective pinions 31, 35, 38, and 42, as indicated in Fig. 25 of the drawings. Each rack-bar, as will be seen from Fig. 12, is provided with a cross-piece 77, forming a pair of side wings or extensions having their lower marginal edges under normal condition resting upon the upper marginal edge of the tipping plate 70. Each rack-bar 75 is also provided at its lower end portion with a part 78, to which is secured a frame 79, having a comparatively large opening 80 and an inclined or cam-shaped marginal edge 81, provided with a depression 82 for the purposes hereinafter set forth. In addition each plate 66 is made with a series of openings, as 83, normally in alignment with the respective key or push-button receiving openings in the face-plate 8, substantially as represented in Fig. 23 of the drawings. In said Fig. 23 the openings in the plate 8 are indicated by the reference character 84, a tubular key-receiving hub 85 being secured about each opening 84, substantially as illustrated. Movably arranged within each hub 85 is a recording key or push-button 86 of the various banks of keys. Each key or push-button consists, essentially, of a tubular body 87, which is slidably arranged in the hub 85 and has a flattened-surface portion 88 and a receiving-depression 89. The outer open portion of each tubular body 87 is closed by means of a cap 90, suitably held in place by a spring-ring 91, arranged in an annular groove in the said parts, as shown. Within the tubular portion of each body 87 is a key-plug 92, having a laterally-extending perforation 93.

for a pin or key 93, the ends of which extend through longitudinal slots 94 in the opposite sides of the tubular body 87 and are fixed in perforations in the opposite sides of the hub 85. Normally the movable parts of the key or push-button are held in the positions indicated more particularly in Fig. 23 of the drawings by means of a coiled spring 95, located within the tubular body 85 between the fixed key-plug 92 and the inner face of the cap 90, said key-plug 92 being employed also to return the depressed keys to their normal initial positions when released from the holding-plates 66 in the manner to be presently described. To limit the return movement of the tubular body 87, a split ring 96 is arranged in an annular groove of the said body, from which a part of such ring 96 projects and is brought against the end of the key-plug 92 to limit the return movement of the parts, as will be clearly understood.

From an inspection of Figs. 21 to 24, inclusive, it will be seen that each key or push-button is located directly in front of the corresponding openings 84 and 83, through which the rear portion of the tubular body 85 of the depressed key is passed and forced directly against the tipping plate 70. This plate having a pivotal or hinged arrangement, as has been stated, is thus moved from its normal initial position indicated in Fig. 21 to the position shown in Fig. 22, whereby the upper edge of the said hinged plate 70 is withdrawn from beneath the right-angled projection or lug 69 of the holding-plate 66; thereby the latter drops or falls a sufficient distance that the edge portions of the respective openings 83 in the plate 66 will arrange themselves back of the end portions of the non-operated keys or push-buttons to prevent the same being pushed in. The upper marginal edge portion of the opening 83, into which the depressed key or push-button has been pushed, thus becomes located in the depression 89 of said depressed key and prevents the return of the said key to its normal initial position until at such time when the cross-bar 58 is raised a sufficient distance and brought against the lower edge 97 of the holding portion or extension 78, connected with the previously-lowered rack-bar 75. A portion of the wings 77 is then brought in contact with the projections 67 of the holding-plate 66, raises the said plate, and withdraws its holding portions from the previous holding engagement with the depressed key or keys. The plate 66 being thus again raised to its normal initial position, the end portion 98' of the spring 73 returns the tipping-plate 70 once more into its holding relation beneath the lug 69 of the plate 66. In the tipping plates 70, (represented more particularly in Figs. 12, 13, 14, 15, and 16,) which are the plates which are to be used with the bank of clerk-initial keys, I have provided the plate with a vertically-ex-

tending opening or slot 98, formed with a pair of vertical guards or bar portions 99 and an enlarged open part 100 at the top, as will be clearly understood from an inspection of said figures. Before the first or initial operation of the machine or apparatus the parts are in the positions indicated in Figs. 14 and 21; but after a key or push-button has once been depressed then these parts are never again in these positions, but in either of the positions shown in Figs. 15, 16, or 22. Now suppose, for instance, clerk B has depressed one of the keys, his key being the second one in the row of keys, as illustrated in Figs. 16 and 22, and another clerk desires to record a sale. The first act of this second clerk is to push the resetting or charging bar 15 in an upward direction. The previously-lowered racks are thereby raised, as has been stated, but before the actuated tipping plate 70 returns to its initial position to return the previously-depressed key or push-button to its starting point an angularly-formed arm 101 is actuated. This arm 101, which extends through a slot 101' in the plate 54, and is attached to the plate 54, said arm 101 also having a head 102, is moved from the lower position indicated in Fig. 16 in an upward direction in the open part 98 until the larger open part 100 is reached, when the tipping plate 70 assumes its position indicated in Fig. 15, with the head 102 resting in said opening 100 and upon the upper edge portions of said guards or bar portions 99. The resetting or charging bar 15 and other parts are thus held in such raised positions until the next key is depressed. The tipping plate 70 is once more forced from its engagement with the head 102, and the charging-bar 15 and its parts and the rack assisted by its spring move downwardly the clerk-initial-indicating drum is properly rotated, and the clerk's initial exposed to view at the window in the front of the casing. Coming now to the plates 66 and 60, located back of the respective sales'-recording keys, it will be noticed that these plates are not provided with such opening or slot 98 and enlarged open part 100, but that each tipping plate 70 (see Figs. 17 and 18) is held against its return to the normal initial position by a latch-dog 63, previously mentioned. As will be seen from an inspection of said Figs. 17, 18, and 20, each latch-dog 63 is made with a holding portion 103, which is held against the lower end portion 104 of the tipping plate 70. Now the clerk-key and parts having been actuated, as above stated, the resetting or charging bar and its parts drop or return to their former position, due to their own weight and the action of the several springs, whereby the cross-bar 58 coming in contact with pins 64 of the latch-dogs 63 sets these latch-dogs in the position indicated in Fig. 19 away from holding contact with the lower portion 104 of the tipping plate. Any of the sales-

recording keys or push-buttons in the respective banks of keys can now be pushed inwardly and the various parts set and actuated in the manner previously described in connection with the bank of clerk-indicating keys.

Immediately after the sales-recording key or keys in the respective banks of keys are depressed a slide 105, (see Fig. 4,) having a portion 106 extending through an opening in the front of the casing 1 and provided with a finger-piece 107, is pushed in an inward direction against the action of a spring 108, whereby an inclined edge 109 of said slide 105 engages with a correspondingly-inclined edge 110 of a finger 111, which is suitably connected with the cross-bar 58, and thereby raises the bar 58 away from the pins 64 of the latch-dogs, which are then sufficiently raised by the action of their springs 65 to bring the parts 103 in holding engagement with the parts 104 of the tipping plates 70, no matter in what positions said plates may be, and whereby all the sales-recording keys and parts relatively connected therewith are held against further operation until all the mechanisms have again been returned to their normal initial positions, as above stated. An open part 112 and a projection 113, both connected with the slide 105, limit the upward movement of the cross-bar 58, at this time the resetting or charging bar 15 and its cross-bar 58 being retained in their raised positions after the slide 105 has been returned to its initial position by its spring 108 by a spring-actuated and pivotally-arranged holding dog or pawl 114, which is forced in holding engagement with the depression or notch 50 of the block 49. At the same time a cam device 115 of any suitable shape and construction engages the lower end 117 of a pivoted and spring-controlled actuating-dog 116, having a bifurcated end 118, which engages a pin or projection 119 of a frame portion 120 of the window shield or shutter 121. A spring 122 connects the said actuating-dog 116 with the frame portion of the said shutter or shield, as clearly illustrated in said Fig. 4 of the drawings. The operation of the various parts are timed so that the shutter or shield 121 is moved away from the window 9 to expose the amount of the recorded sale to view, the said shutter or shield being again moved in front of the window when the next clerk moves the resetting or charging bar 15 in an upward direction for the purpose of resetting the various mechanisms.

Referring now to Figs. 4 and 7 of the drawings, it will be seen that I have arranged in bearings 123 a shaft 124, upon which are suitably secured a number of counting devices 125, in the present case three of such devices being employed and corresponding to the number of "cents" and "dollars" indicating drums used with the cash-register.

Each counting device 125 consists of a number of radially-extending arms, upon each of which is suitably secured a register or total-adder 126, the number of total-adders connected with each counting device corresponding to the number of clerk-indicating keys used with the cash-register. Each total-adder is provided with the usual spindle-carrying indicating-disks, and each shaft or spindle has a star-wheel 127, with the prongs of which are brought in engagement laterally-extending pins 128, projecting from the sides of the rack-bars 75, which actuate the drums for indicating the amount of the sale or sales made, these pins 128 engaging with and actuating the star-wheels during the downward movements of the said rack-bars. That the proper clerk's total-adders are brought directly back of the windows 129 in the face-plate 8 when the rack-bar 75 to the right of Fig. 9 of the drawings moves downwardly the teeth of the rack are made to actuate a pinion 130, which being in engagement with a gear 131 upon the shaft 124 causes the latter to make a certain predetermined revolution, according to the downward movement of the rack, and thereby the desired clerk's total-adder is rotated directly back of the window 129, in which positions the registering parts of these total-adders are actuated by the pins 128 of the downwardly-moving racks being brought in operative engagement with the star-wheels of the total-adders, as will be clearly evident. During the upward movements of the actuated rack-bars 75 the pins 128 are thrown out of engagement with the said star-wheels 127 by the upward movement of the bar 47 of the resetting or charging lever or bar 15 by forcing an arc-shaped depression 132 in said bar 47 from a portion of a wheel or disk 133, against which it normally rests. This wheel or disk 133 is rotatively connected with the shaft 124 by a bearing 134. A spring 135 on said shaft 124 has its one end secured upon said shaft 124, and its other end is fastened against a stop 136, and thus tends to retain the position of the wheel or disk 133 in said depression 132 under normal conditions; but said disk or wheel during the upward movement of said bar 47 being forced from said depression 132 causes the shaft 124 to slide sidewise in its bearings 123, whereby the spring 135 is in compression, and the star-wheels 127 being moved with the said shaft 124 are thrown out of their paths of engagement with the pins of the rack-bars 75, and hence remain inoperative. When the resetting or charging bar 15 is again returned to its lowered position and the bar 47 is returned with it, the recess 132 and wheel or disk 133 are again brought into their operative relation by the action of the said spring 135, and the shaft slides back to its former position for the purposes just stated.

Referring now again to Fig. 4 of the draw-

ings, the slide 105 is also used for releasing a locking or holding mechanism connected with the cash-drawer 7. From the said figure it will be seen that the said slide 105 is provided with a rearwardly-projecting stem 137, which is movably arranged in bearing portions of a bracket 138, suitably secured to the lower part of the inner face of the back 3 of the casing 1. This stem 137 is provided with an upwardly-extending inclined edge portion 139, upon which rests and rides a pin or projection 140, extending from the side of a bolt 141. Thus when the slide 105 is pushed in an inward direction the said bolt 141, which moves in a bearing portion 142 in the upper part of the bracket 138 and in an opening in a guide-plate 143, will have its lower end 144 withdrawn from holding engagement with an opening 146 of a bracket or plate 145, secured to the said drawer, and the latter can be withdrawn. A second bracket 147 is secured to said bracket 138, said bracket 147 having pivotally attached thereto a bell-crank comprising a pair of crank-arms 148 and 149, a spring 150 having its respective ends secured to the said bell-crank arm 148 and the bolt 141, substantially as shown. The purpose of this spring 150 is to cause an offset 151 at the lower portion of the bolt 141 to rest upon the upper edge of the guide-plate 143 to retain the bolt in its raised position until the drawer is again pushed into the casing 1, when the bracket or plate 145 of said drawer is brought in forcible contact with a finger or extension 152 upon said bolt 141, and thereby brings the bolt once more into its normal initial position, which causes the bolt to again drop into its holding or locking engagement with the bracket 145 of the drawer. That the said cash-drawer may be locked against withdrawal from the casing 1, if desired, when the cash-register mechanisms are operated I have secured to the crank-arm 149 of the bell-crank a link 153, which extends in an upward and forward direction in the casing 1, being connected at its upper end with a crank-arm 154, pivoted upon a bracket 155 upon the inner face of the face-plate 8 and having a finger-piece 156, which can be reached through an opening 157 in said face-plate, said opening being ordinarily closed by a slide 158, which may be locked so as not to be manipulated by the clerk. When said finger-piece 156 is pulled in an outward direction, then said link 153 will force the crank-arm 149 in a downward direction, thereby forcing the crank-arm 148 over upon the opposite edge of the bolt 141, and its spring 150 will be arranged upon the other side of the pivotal center of the bell-crank. The result will be that the bell-crank is thereby held against pivotal movement, and when the slide 105 is pushed in it will be seen that the raised bolt 141 immediately drops back into its locked engagement with the bracket 145

of the drawer and prevents the drawer from being pulled out by the operator. The upper end portion of the bolt 141 may also be employed for striking a gong 159 by being brought in lifting engagement with the end of a pivoted and spring-controlled tripping-lever 160, which actuates a spring-controlled striking-arm 161, as will be clearly understood from an inspection of Fig. 5 of the drawings. The said striking-arm 161 has a lip or finger 162 pivotally connected therewith, which permits the return of the several parts to their initial positions after the bolt has again dropped to its starting-point.

In addition to the previously-described devices and mechanisms a means may be employed for throwing the counting devices out of operation, which is desirable when the drawer is to be opened for the purposes of making change when no sale is to be recorded or for the purpose of removing the cash from the drawer. This is accomplished by an initial key 163, preferably of the same construction as the clerk-indicating keys illustrated in Figs. 23 and 24 of the drawings, the tubular body or barrel 164 in this case being attached to a plug 165, which is chamfered at its inner end and when forced in an inward direction engages the correspondingly-chamfered end portion of the counter-carrying shaft 124 and moves the said shaft laterally in its bearings against the action of the spring 135, whereby the gear 131 is thrown from its engagement with the correspondingly-placed rack-bar 75, and the mechanism of the cash-register can be operated without actuating the counting devices. The said key 163 when depressed remains in its depressed position on account of an edge portion 166 of an opening 167 in an extension 168, connected with the guide-plate 66, being brought in holding engagement with a depression 169 in the tubular body 164, as clearly represented in Figs. 12, 13, 23, and 24 of the drawings, until again released by the upward movement of the resetting or charging bar 15 in the manner previously described.

A combined ticket and pad or book orienting device (represented more particularly in Figs. 30 and 31 of the drawings) may be used with the cash-register mechanism, if desired. The device consists essentially of a base 170, which is secured upon the inner face of the back of the cash-register, preferably in an adjustable position, by means of a bracket 171 and a pivotal pin or bolt 172. The said base 170 is provided with a pair of upwardly-extending standards 173, each standard being provided with an elongated hole 174, in which is rotatively arranged a spindle carrying between a peculiarly-constructed shell or casing 176 a roll of paper or tape 177. This shell casing is made with a forwardly-extending arm or portion 178, with which is pivotally connected the upper

end of a link 179, which is provided at its lower part with an elongated opening or slot 180, in which is slidably arranged a pivot 181, connected with the one end of the cross-bar 5 58, previously described, and which is actuated during the upward movement of the re-setting or charging bar 15. The standard 173 is also made with the oppositely-extending arms 182 and 183, one of which, as 182, is 10 provided with a tapered or inclined edge 184 and the other arm 183 having an upwardly-extending member 185. The shell or casing 176 is made with a projection 186, having a block 187 secured thereto, the said 15 shell or casing being closed at 188, as indicated in dotted outline, and having an open edge portion 189, back of which is located a tape feed or guide 190. A pair of pawls or dogs 191 and 192 are respectively pivotally 20 connected with the standard and the shell or casing, the pawl 191 being for the purpose of properly guiding the paper or tape through the guide 190 when the shell moves in the direction of the arrow in said Fig. 30 and the 25 other pawl or dog 192 being for the purpose of holding the edge portion of the tape in place after the ticket has been severed off by the knife or cutter 193. This knife or cutter is slidably arranged between a pair of guides 30 194 and when brought in contact with a projection 196, extending from a fixed bracket 195, is forced against the tape and a ticket of the proper length is cut from said tape and, with the portion 197 of the shell or casing 35 176, is presented directly beneath the printing wheels or rollers 198 and 199. During the rotary movement of the shell 176 in the direction of the said arrow in said Fig. 30 an inking-roller 200, which is operatively secured upon a lever 201, fulerun upon the bracket 178, is brought against the printing wheels or rollers 198 and 199 to supply the printing devices of said rollers with ink. The printing upon the ticket is accomplished 40 by an upward vertical movement of this entire device, when the slide 105 is forced in its inward direction by means of a stem 202, which has a reciprocatory movement in a bearing 203, extending from the lower 45 surface of the base 170. This stem 202 is actuated from a link 204, which is pivotally attached to a crank-arm 205, secured upon a spindle 206, adapted to oscillate in bearings 207, a second crank-arm 208 being secured 50 upon said spindle 206 and provided with a roller 209, which is operatively arranged in an elongated opening 210 in the slide 105 and whereby an inward movement of said slide 105 will produce an upward movement of the 55 device, thereby bringing the ticket against the said printing-wheels 198 and 199, while an outward movement of said slide 105 returns the device to its lowered position. An arm 211, provided with a hook end 212 in 60 65 slide engagement with a ratchet-wheel

213, connected with the printing wheel or roller 199, produces a rotary movement of said wheel or roller 199, and the latter being in rolling contact with the wheel or roller 198 the said roller or wheel 198 is also actuated. 70 Movably arranged upon the spindle 175 is an arm 214, provided with a pin-point 215, which engages the ticket and forces the same into a delivery-chute 216, the said arm 214 having a second arm portion 217 and a spring 75 218 attached thereto and to the arm 185, which forces said arm 214 into the position indicated in Fig. 30 to force the ticket into the said chute 216. A pin or projection 219 extends from the side of said arm 214 and is 80 brought in engagement with a plate or bar 220, secured to the arm 185 to hold said arm 214 in its returned position (indicated in Fig. 31) when the shell or casing 176 and its parts have been returned to their normal 85 initial positions by the downward movement of the cross-bar 58. The arm 201, which carries the inking-roller 200, is provided at its lower end with a roller 222, which is forced upon the incline 184 of the arm 182 by 90 the action of a spring 221, which is attached to said arm 201 and the bracket 178 to bring said inking-roller 200 away from the receiving-opening of the ticket-chute 216. A spring-dog 223 is secured to the inner surface 95 of the casing 1, having a holding portion in engagement with a tooth of the ratchet-wheel 213 to prevent the turning of the printing wheels or rollers in the wrong directions. Upon a cross-bar or spindle 224 is 100 pivotally secured a pad-receiving plate 225, extending through an opening 227 in the front of the casing 1, and said plate 225 being provided with an opening 226. Said plate 225 is connected with a cradle or rocking 105 frame 228, which has a pin 229 and a roller 231 at one end and oscillates at its other end upon a spindle 230, which extends from a link or connecting-arm 232, pivotally connected at its lower end upon the said spindle 110 175. Thus the upward movement of the main device causes a swinging action of the rocking frame and plate 225, bringing its opening 226 directly over the upper surfaces of the printing wheels or rollers 198 and 199 115 and printing upon the pad which has been slipped upon said plate 225 and is held in position by the spring-plate 233 and a cross-bar 234, connected with said plate 233. When the cutter or knife 193 is in its cutting position, it is brought down upon a spring-controlled and oscillatory anvil 235, as indicated in Fig. 30. A stop 236 limits the return of all the parts to their normal initial positions, as will be clearly evident from an inspection 120 of said Figs. 30 and 31 of the drawings. 125

In Figs. 32 and 33 I have illustrated a modified form of tape-printing device. In this construction the main spindle 175 is provided with a pair of oscillating frame-plates 130

237, adapted to be actuated from the bar or link 179, which is pivotally connected with an ear or projection 238 on one of said frame-plates 237. The said frame-plates 237 are made with other perforated ears 239 and a spindle 240, which carries a tape roll 241, the tape passing over a roller 242, which is supported between a pair of ears 243, at which point the tape is carried up against the printing wheels or rollers 244 in the same manner set forth in connection with the construction represented in Figs. 30 and 31 of the drawings, the printed portion of the tape passing upon a winding-drum 245, having a ratchet-wheel 246, actuated from a pawl 247 in any usual and well-known manner. One of the ears 243 of the one frame-plate is provided with a pin 248, on which oscillates a lever 249, which carries an inking roll or pad 250. This roll or pad is brought in slidable contact with the printing wheel or roller during the oscillatory movements of the frame-plates 237, a spring 251 being secured at one end to said lever 249 and at the other end to the frame-plate 237 to normally retain said lever against a pin or projection 252, which extends from the side of the frame-plate 237, substantially as illustrated. The construction of the remaining parts and their operations are the same as those described in connection with the printing device illustrated in said Figs. 30 and 31 of the drawings and need not be further described here.

Referring now to Figs. 4, 6, 7, and 10 of the drawings, it will be seen that there may be used with the cash-register mechanism a number of phonographs or other suitably-constructed talking-machines 253. These correspond to the number of banks of sales recording or indicating keys exposed at the front of the cash-register casing, and in consequence they correspond also to the number of rack bars or arms 75 employed. In the present construction the cash-register is provided with four phonographs, the record-cylinder of one of the phonographs or talking-machines being used for the purpose of producing in imitation of the human voice the name or symbol of the clerks, as "A," "B," "C," "D," &c., another record-cylinder being used to call out the amount of the sale in dollars, and the other two record-cylinders being used to call out the sale in cents—as, for instance, "ninety" on one cylinder and "two" on the other cylinder, thus reproducing in imitation of the voice the words "ninety-two." These phonographs, which are of the usual construction, are arranged upon a base-plate 254, which is connected with a support 255, suitably secured upon a bracket 256, which extends from the inner face of the face-plate 8, as clearly illustrated in Fig. 10 of the drawings. As has been previously stated, each rack bar or arm 75 is made with a hold-

ing portion 78 and frame 79, having the opening 80 and inclined edge 81 and depression 82. When the rack bars or arms are in their raised positions, (indicated to the left in Figs. 7 and 9 of the drawings,) a pivotally-arranged extension 257, connected with the oscillating frame 258, which carries the usual reproducing part 259, provided with a stylus, is arranged in the depression 82 and is held there by frictional engagement, and when the rack bar or arm is lowered the said extension 257 moves with said depression and brings the stylus of the said reproducing part 259 substantially opposite the fixed point upon the record 260, the position and location of the parts being controlled and governed by the downward movement of the rack bar or arm 75. As soon as the rack-bar has ceased to move, however, the tendency of the part 259 is to move still farther, owing to the force of gravity, thereby forcing the pivotally-arranged extension 257 from the depression 82 directly upon the inclined marginal edge 81 and causing it to assume the position shown in Figs. 9 and 10 at the right of said figures, whereby the frame 258 is sufficiently oscillated and the stylus has been brought in its operative and sound-reproducing relation with the record 260. The parts of the frame portion 258 have thus been brought in operative engagement with the rotary screw-rod 261 of the phonograph-frame, and the stylus now moves along the revolving record in the manner usual to the ordinary construction of phonographs. The various cylinders 262 of the several phonographs have a belt 263 suitably arranged about them, the said belt being operated from a driving-wheel 264, which is driven from a spring-motor 265 (see Figs. 27 and 28) by means of the intermediately-placed gear mechanism 266. This motor is of the usual construction of motor employed with phonographs and is held against movement by a spring-bolt 267, having a teat or projection 268 extending through a slot 269 in the side of a barrel 270 and in holding engagement with a stop 271 upon the spring-barrel of the motor. As soon as the cross-bar 58 is moved upwardly by the inward movement of the slide 105 a pivotally-arranged and spring-controlled latch 272, connected with the said cross-bar 58, engages with a right-angled extension or arm 273 on said bolt 267 and raises the latter sufficiently in its barrel to throw the teat 268 from its holding engagement with the stop 271. At the same time a spring 274 produces a slight rotary movement of the spring-bolt 267 in its barrel, withdrawing its upper inclined holding portion 275 from engagement with the arm 276 of a usual holding device 277, and the motor mechanism is thereupon set in motion, whereby the record-cylinders of the phonographs are revolved. As soon as the cross-bar 58 has moved the required distance and 13c

is held by the latch 114, previously described, the spring-latch 272 has moved beyond the extension or arm 273 of the spring-bolt 267, whereby the latter is forced down 5 into its initial position, and its teat 268, engaging with the next stop 271, brings the upper surface of said bolt in its holding relation with the arm 276 of the holding device and once more arrests all motion of the moving 10 parts of the phonographs.

Referring now to the bottom view of the motor-winding mechanism represented in Fig. 11 of the drawings, it will be seen that when the cross-bar 58 is moved in an upward 15 direction a flexible connection 278, attached to said bar 58 and passing over a pulley or wheel 279, will be moved in the direction of the arrow in said Fig. 11, whereby an arm or lever 280, to which the other end of the spring 20 is secured, will by means of a connection-spring 281 produce a movement of an arm 282. This arm 282 has a spring-dog 283, which is thus made to engage the teeth of a ratchet-wheel 284, secured to the main spindle or winding-arbor of the motor 265 for rewinding the mainspring of the motor, as will 25 be clearly understood. A spiral spring 285 is arranged and connected with the said parts in such a manner that upon the downward 30 movement of the cross-bar 58 the said spring 285 will return the said arms 280 and 281 to their normal initial positions to be again ready for action upon the next upward movement of the bar 58 when the mechanisms of 35 the cash-register are operated. The spring 285 has this further advantage that should the motor-spring become wound to its fullest extent the arm or lever 280 can still be moved back and forth, merely distending the coils of 40 the spring 281 without actuating the arm 282, and there will therefore be no danger of any of the parts becoming broken or rendered inoperative by too tightly winding the spring.

From an inspection more especially of Fig. 45 27 of the drawings it will be seen that the release of the motor-spring is occasioned by the upward movement of the bar 58, and all the phonographs are simultaneously set in operation with the various annunciators down 50 upon the several records. That, however, there may be no confusion of sounds in making the original records it is merely a question of timing in speaking in successive order into the several recording-horns of the several records to be produced. Thus when the several records are arranged upon their respective receiving-cylinders of the phonographs of the cash-register they all revolve simultaneously with the corresponding annunciators 55 in contact with their respective records. The various records, however, have been produced in such a manner that when one annunciator is in operative engagement with its record the other annunciators are moving upon 60 blank spaces of their correspondingly-placed

records. In this manner there is never more than one annunciator in operative sound-producing engagement with its record and there can be no confusing sounds, as will be clearly evident. The sounds are produced 70 in successive order and travel through a series of conveying-tubes 286, which are slidably arranged in and connected with portions of other tubes 287, these tubes 287 being in communication with a conveying duct or 75 tube 288, from which the sound travels through the tube or conveyer 289 and a flexible tubular connection 290 into the sound-magnifying horn or trumpet 291, which is suitably connected with the upper portion of 80 the cash-register casing and extends from the top thereof, substantially in the manner illustrated in the several figures of the drawings.

I am fully aware that many changes may be made in the arrangements and combinations of the various devices and parts, as well as in the details of the construction of the same, without departing from the scope of this invention. Hence I do not limit my invention to the exact arrangements and combinations of the devices and parts as described in the foregoing specification and as illustrated in the accompanying drawings, nor do I confine myself to the exact details of the construction of the said parts.

Having thus described my invention, what 95 I claim is—

1. In a cash-register, the combination, with an indicating mechanism, of a talking-machine comprising a number of record-receiving cylinders, a record upon each cylinder, and annunciators, and means for actuating both said indicating mechanism, and all the record-receiving cylinders simultaneously, said annunciators making contact with all 105 the records at the same time, but arranged to reproduce sounds of the various records in successive order, without a confusion of sounds, substantially as and for the purposes set forth.

2. In a cash-register, the combination, with an indicating mechanism, of a talking-machine comprising a number of record-receiving cylinders, a record upon each cylinder, and annunciators, a spring mechanism, and means for actuating said indicating mechanism, said spring mechanism, and all the record-receiving cylinders simultaneously, said annunciators making contact with all the records at the same time, but arranged to reproduce sounds of the various records in successive order, without a confusion of sounds, substantially as and for the purposes set forth.

3. In a cash-register, the combination, with a sales-indicating mechanism, of a total-adding device, a talking-machine comprising a number of record-receiving cylinders, a record upon each cylinder, and annunciators, and means for actuating said indicating

mechanism, said total-adding device and all the record-receiving cylinders simultaneously, said annunciators making contact with all the records at the same time, but arranged to 5 reproduce sounds of the various records in successive order, without a confusion of sounds, substantially as and for the purposes set forth.

4. In a cash-register, the combination, 10 with a sales-indicating mechanism, of a total-adding device, a talking-machine comprising a number of record-receiving cylinders, a record upon each cylinder, and annunciators, a printing mechanism, and means for actuating 15 said indicating mechanism, said total-adding device, said printing mechanism, and all the record-receiving cylinders simultaneously, said annunciators making contact with all the records at the same time, but arranged to 20 reproduce sounds of the various records in successive order, without a confusion of sounds, substantially as and for the purposes set forth.

5. In a cash-register, the combination, 25 with a series of keys and means for locking said keys after one of said keys has been depressed, of an indicating mechanism, a talking-machine comprising a number of record-receiving cylinders, a record upon each cylinder, and annunciators, and means for actuating 30 all the record-receiving cylinders simultaneously, said annunciators making contact with all the records at the same time, but arranged to reproduce sounds of the various 35 records in successive order, without a confusion of sounds, substantially as and for the purposes set forth.

6. In a cash-register, the combination, 40 with a series of keys and means for locking said keys after one of said keys has been depressed, of an indicating mechanism, a talking-machine comprising a number of record-receiving cylinders, a record upon each cylinder, and annunciators, a printing mechanism, 45 and means for actuating said indicating mechanism, said printing mechanism, and all the record-receiving cylinders simultaneously, said annunciators making contact with all the records at the same time, but arranged 50 to reproduce sounds of the various records in successive order, without a confusion of sounds, substantially as and for the purposes set forth.

7. In a cash-register, the combination, 55 with a series of keys and means for locking said keys after one of said keys has been depressed, of a sales-indicating mechanism, a total-adding device, said indicating mechanism and total-adding device both being actuated from a depressed key, a talking-machine comprising a number of record-receiving cylinders, a record upon each cylinder, and annunciators, and means for actuating 60 all the record-receiving cylinders simultaneously, said annunciators making contact

with all the records at the same time, but arranged to reproduce sounds of the various records in successive order, without a confusion of sounds, substantially as and for the purposes set forth.

8. In a cash-register, the combination, 70 with a series of keys and means for locking said keys after one of said keys has been depressed, of a sales-indicating mechanism, a total-adding device, said indicating mechanism and total-adding device both being actuated from a depressed key, a talking-machine comprising a number of record-receiving cylinders, a record upon each cylinder, and annunciators, a printing mechanism, and means for actuating 75 said printing mechanism, and all the record-receiving cylinders simultaneously, said annunciators making contact with all the records at the same time, but arranged to reproduce sounds of the various 80 records in successive order, without a confusion of sounds, substantially as and for the purposes set forth.

9. In a cash-register, the combination, 85 with a normally inoperatively held indicating mechanism, of a resetting device for bringing said indicating mechanism in condition to be operated, and permitting it to return to its normal initial position by gravity, a total-adding device actuated by the return 90 movement of said indicating mechanism, a talking-machine, and means for actuating said talking-machine, substantially as and for the purposes set forth.

10. In a cash-register, the combination, 95 with a normally inoperatively held indicating mechanism, of a resetting device for bringing said indicating mechanism in condition to be operated and permitting it to return to its normal initial position by gravity, 100 a total-adding device actuated by the return movement of said indicating mechanism, a talking-machine, a printing mechanism, and means for actuating the said talking-machine, and said printing-machine, substantially 105 as and for the purposes set forth.

11. In a cash-register, the combination, 110 with an indicating-drum, and a normally inactive drum-actuating means for producing a rotary motion of said drum when released, 115 of means for releasing said drum-actuating means, a talking-machine, means connected with said drum-actuating means for setting the reproducer of the talking-machine, and means for operating said talking-machine, 120 substantially as and for the purposes set forth.

12. In a cash-register, the combination, 125 with an indicating-drum, and a normally inactive drum-actuating means for producing a rotary motion of said drum when released, 130 of means for releasing said drum-actuating means, a talking-machine, means connected with said drum-actuating means for setting the reproducer of the talking-machine, a

printing mechanism, and means for operating the talking-machine and said printing mechanism, substantially as and for the purposes set forth.

5 13. In a cash-register, the combination, with an indicating-drum, and a normally inactive drum-actuating means for producing a rotary motion of said drum when released, of means for releasing said drum-actuating 70
10 means, a total-adding device, a talking-machine, means connected with said drum-actuating means for actuating said total-adding device, means connected with said drum-actuating means for setting the reproducer of 75
15 the talking-machine, and means for operating the talking-machine, substantially as and for the purposes set forth.

14. In a cash-register, the combination, with an indicating-drum, and a normally inactive drum-actuating means for producing a rotary motion of said drum when released, of means for releasing said drum-actuating 80
20 means, a total-adding device, a talking-machine, means connected with said drum-actuating means for actuating said total-adding device, means connected with said drum-actuating means for setting the reproducer of 85
25 the talking-machine, a printing mechanism, and means for operating the talking-machine and said printing mechanism, substantially as and for the purposes set forth.

30 15. In a cash-register, the combination, with a main shaft, a pinion and indicating-drum on said shaft, and a rack-bar in engagement with said pinion, of a series of keys 90
35 adapted to release said rack-bar and cause it to rotate said indicating-drum, a talking-machine, and means connected with said rack-bar for setting the reproducer of the 95
40 talking-machine, substantially as and for the purposes set forth.

45 16. In a cash-register, the combination, with a main shaft, a pinion and indicating-drum on said shaft, a normally inactive rack-bar in engagement with said pinion, of a resetting device for bringing the parts in condition to be operated, a series of keys adapted to release said rack-bar and cause it to rotate the indicating-drum, a talking-machine, 100
50 and means connected with said rack-bar for setting the reproducer of the talking-machine, substantially as and for the purposes set forth.

55 17. In a cash-register, the combination, with a main shaft, a pinion and indicating-drum on said shaft, and a rack-bar in engagement with said pinion, of a series of keys 105
60 adapted to release said rack-bar and cause it to rotate said indicating-drum, a talking-machine, and means connected with said rack-bar for setting the reproducer of the talking-machine and said printing device,

substantially as and for the purposes set forth.

18. In a cash-register, the combination, with a main shaft, a pinion and indicating-drum on said shaft, a normally inactive rack-bar in engagement with said pinion, of a resetting device for bringing the parts in condition to be operated, a series of keys adapted to release said rack-bar and cause it to rotate the indicating-drum, a talking-machine, means connected with said rack-bar for setting the reproducer of the talking-machine, a slide, and a key connected with said slide for operating the talking-machine and said printing device, substantially as and for the purposes set forth. 80
70
75
85

19. In a cash-register, the combination, with a casing, and a drawer slidably arranged in said casing, of a main shaft, a pinion and indicating-drum on said shaft, a rack-bar in engagement with said pinion, a series of keys 85
90
95 adapted to release said rack-bar and cause it to rotate said indicating-drum, a talking-machine, means connected with said rack-bar for setting the reproducer of the talking-machine, a slide for releasing the talking-machine-operating mechanism, and means connected with said slide for releasing the drawer, substantially as and for the purposes set forth.

20. In a cash-register, the combination, with a casing, and a drawer slidably arranged in said casing, of a main shaft, a pinion and indicating-drum on said shaft, a normally inactive rack-bar in engagement with said pinion, a resetting device for bringing the parts in 100
105
110 condition to be operated, a series of keys adapted to release said rack-arm and cause it to rotate said indicating-drum, a talking-machine, means connected with said rack-arm for setting the reproducer of the talking-machine, a slide for releasing the talking-machine-operating mechanism, and means connected with said slide for releasing the drawer, substantially as and for the purposes set forth.

110 21. In a cash-register, the combination, with a main shaft, a pinion and indicating-drum on said shaft, and a rack-bar in engagement with said pinion, of a series of keys, means actuated from said keys to release said 115
120
125 rack-bar and cause it to rotate said indicating-drum, consisting, of a holding-plate having key-receiving openings, and a tipping plate back of said holding-plate, a talking-machine, and means connected with said rack-bar for setting the reproducer of the talking-machine, substantially as and for the purposes set forth.

22. In a cash-register, the combination, with a main shaft, a pinion and indicating-drum on said shaft, of a normally inactive rack-bar in engagement with said pinion, a series of keys, means actuated from said keys

to release said rack-bar and cause it to rotate said indicating-drum, consisting of a holding-plate having key-receiving openings, and a tipping plate in engagement with said holding-plate, a resetting device for actuating said tipping plate, a talking-machine, and means connected with said rack-bar for setting the reproducer of the talking-machine, substantially as and for the purposes set forth.

23. In a cash-register, the combination, with an indicating mechanism comprising a rack-bar having an extension provided with an open frame, of a talking-machine and its sound-reproducer provided with a pivotal extension in operative engagement with a portion of said open frame, substantially as and for the purposes set forth.

24. In a cash-register, the combination, with an indicating mechanism comprising a rack-bar having an extension provided with an open frame, a tipping plate with which said rack-bar is in supporting engagement, and means for disengaging said tipping plate from said rack-bar, of a talking-machine and its sound-reproducer provided with a pivotal extension in operative engagement with a portion of said open frame, substantially as and for the purposes set forth.

25. In a cash register, the combination, with an indicating mechanism comprising a rack-bar having an extension provided with an open frame, a series of keys and a holding-plate provided with key-receiving openings adapted to be brought in locking engagement with said keys, of a talking-machine and its sound-reproducer provided with a pivotal extension in operative engagement with a portion of said open frame, substantially as and for the purposes set forth.

26. In a cash-register, the combination, with an indicating mechanism comprising a rack-bar having an extension provided with an open frame, a series of keys and a holding-plate provided with key-receiving openings adapted to be brought in locking engagement with said keys, of a talking-machine and its sound-reproducer provided with a pivotal extension in operative engagement with a portion of said open frame, and a resetting device for releasing said holding-plate from its locked engagement with the keys, substantially as and for the purposes set forth.

27. In a cash-register, the combination, with a main shaft, a pinion and indicating-drum on said shaft, of a rack-bar in engagement with said pinion, a pair of oppositely-extending projections upon said rack-bar, and a pivoted tipping plate normally in supporting engagement with the projections of said rack-bar, substantially as and for the purposes set forth.

28. In a cash-register, the combination, with a main shaft, a pinion and indicating-drum on said shaft, of a rack-bar in engage-

ment with said pinion, a series of keys, a holding-plate provided with key-receiving openings adapted to be brought in holding engagement with the keys, and a tipping plate in supporting engagement with said holding-plate and said rack-bar, substantially as and for the purposes set forth.

29. In a cash-register, the combination, with a main shaft, a pinion and indicating-drum on said shaft, of a rack-bar in engagement with said pinion, a series of keys, a holding-plate provided with key-receiving openings adapted to be brought in holding engagement with the keys, a tipping plate in supporting engagement with said holding-plate and said rack-bar, said tipping plate being provided with an elongated opening, and a resetting device having a portion slidably arranged in said elongated opening and in engagement with said tipping plate, substantially as and for the purposes set forth.

30. In a cash-register, the combination, with a main shaft, a pinion and indicating-drum on said shaft, of a rack-bar in engagement with said pinion, a series of keys, a holding-plate provided with key-receiving openings adapted to be brought in holding engagement with the keys, a tipping plate in supporting engagement with said holding-plate and said rack-bar, said tipping plate being provided with an elongated opening, a resetting device having a portion slidably arranged in said elongated opening and in engagement with said tipping plate, and a spring-controlled latch-dog normally in engagement with said resetting device for holding engagement with said tipping plate when released from said resetting device, substantially as and for the purposes set forth.

31. In a cash-register, the combination, with an indicating mechanism, of a slidably-arranged holding-plate provided with a key-receiving opening, and a key having a slotted holding portion adapted to enter said key-receiving opening for holding engagement therewith, a pivoted tipping plate a resetting device comprising a cross-bar, and a spring-controlled latch-dog normally in holding engagement with said cross-bar for holding engagement with said tipping plate when released from said cross-bar, substantially as and for the purposes set forth.

32. In a cash-register, the combination, with an indicating mechanism of a laterally-movable shaft, a series of detail-adders concentrically disposed around said shaft, a series of keys, said detail-adders having a combined intermittent rotary movement around said shaft, substantially as and for the purposes set forth.

33. In a cash-register, the combination, with an indicating mechanism, of a laterally-movable shaft, a series of detail-adders concentrically disposed around said shaft, a series of numbering-disks in each detail-adder,

- a series of keys, said detail-adders having a combined intermittent rotary movement around said shaft, and means for actuating the numbering-disks independent of the rotation of the detail-adders, substantially as and for the purposes set forth.
34. In a cash-register, the combination, with a casing, of a bank of clerk-indicating keys, and a bank of sales-indicating keys, a shaft in said casing, a series of detail-adders concentrically disposed around said shaft, each set of detail-adders corresponding in number to the number of clerk-indicating keys, means actuated from said clerk-indicating keys for intermittently rotating all the detail-adders, and thereby bringing one of said adders into its registering position, a series of numbering-disks in each detail-adder, and means for actuating the numbering-disks of the detail-adder previously rotated into its registering position, substantially as and for the purposes set forth.
35. In a cash-register, the combination, with an indicating mechanism, of a laterally-movable shaft, a series of detail-adders concentrically disposed around said shaft, and means for moving said shaft laterally and throwing said detail-adders out of operation, substantially as and for the purposes set forth.
36. In a cash-register, the combination, with an indicating mechanism, of a resetting device comprising a bar arranged upon the outside of the register-casing, and a second bar connected with said bar but arranged upon the inside of the casing, a holding-dog for retaining said resetting device in a raised position, and means on said inner bar for producing a disengaged relation of said holding-dog with said resetting device, substantially as and for the purposes set forth.
37. In a cash-register, the combination, with a main shaft, a pinion and indicating-drum on said shaft, a normally inactive rack-bar in engagement with said pinion, of a resetting device for bringing the parts in condition to be operated, a series of keys adapted to release said rack-bar and cause it to rotate the indicating-drum, a talking-machine, means connected with said rack-bar for setting the reproducer of the talking-machine, and means connected with said resetting device for returning said reproducer to its normal initial position, substantially as and for the purposes set forth.
38. In a cash-register, the combination, with a main shaft, a pinion and indicating-drum on said shaft, a normally inactive rack-bar in engagement with said pinion, of a resetting device for bringing the parts in condition to be operated, a series of keys adapted to release said rack-bar and cause it to rotate the indicating-drum, a talking-machine, means connected with said rack-bar for setting the reproducer of the talking-machine,
- 5 and means connected with said resetting device for returning said reproducer to its normal initial position, consisting, essentially, of a cross-bar connected with said resetting device, and an upwardly-extending finger adapted to be brought in engagement with a portion of the reproducer of the talking-machine, substantially as and for the purposes set forth.
39. In a cash-register, the combination, with a main shaft, a pinion and indicating-drum on said shaft, a normally inactive rack-bar in engagement with said pinion, of a resetting device for bringing the parts in condition to be operated, a series of keys adapted to release said rack-bar and cause it to rotate the indicating-drum, a talking-machine, means connected with said rack-bar for setting the reproducer of the talking-machine, and means connected with said resetting device for returning said reproducer to its normal initial position, consisting, essentially, of a cross-bar connected with said resetting device, and an upwardly-extending finger adapted to be brought in engagement with a portion of the reproducer of the talking-machine, substantially as and for the purposes set forth.
40. In a cash-register, the combination, with a spring-controlled slide 105, of a printing device, a printing-roll, a pad-carrying frame, means between said frame and said slide for forcing the pad against the printing-roll, consisting of a spring-plate 233 and a cross-bar 234, substantially as and for the purposes set forth.
41. In a cash-register, the combination, with a spring-controlled slide 105, of a printing device, a printing-roll, a frame, and an oscillatory paper-carrying shell in said frame, means for oscillating said shell, means for feeding the paper beneath said printing-roll, and means between the said frame and said slide for forcing the paper against the printing-roll, substantially as and for the purposes set forth.
42. In a cash-register, the combination, with a spring-controlled slide 105, of a printing device, a printing-roll, a frame, and an oscillatory paper-carrying shell in said frame, means for oscillating said shell, means for feeding the paper beneath said printing-roll, a cutter for severing the paper to provide a ticket, and means between the said frame and said slide for forcing the ticket against the printing-roll, substantially as and for the purposes set forth.
43. In a cash-register, the combination, with a casing and a drawer, of a slide 105, a bracket 138 having bearing portions, a rearwardly-extending stem connected with said slide, said stem being movably arranged in

the bearing portions of said bracket, a bolt, means on said drawer with which said bolt is normally in locked engagement, and means on said stem and bolt for lifting said bolt 5 from its locked engagement with the drawer, consisting of an inclined edge portion 139 on said stem, and a projection on said bolt with which said edge portion 139 is brought in engagement for raising said bolt, substantially 10 as and for the purposes set forth.

44. In a cash-register, the combination, with a casing and a drawer, of a slide 105, a bracket 138 having bearing portions, a rearwardly-extending stem connected with said 15 slide, said stem being movably arranged in the bearing portions of said bracket, a bolt, means on said drawer with which said bolt is normally in locked engagement, means on said stem and bolt for lifting said bolt from 20 its locked engagement with the drawer, consisting of an inclined edge portion 139 on said stem, and a projection on said bolt with which said edge portion 139 is brought in engagement for raising said bolt, and a gong- 25 striking means adapted to be actuated from said bolt, substantially as and for the purposes set forth.

45. In a cash-register, the combination, with a casing having a window 9, of a shaft in 30 said casing, a pinion and indicating-drum on said shaft, a drum-actuating means, a resetting device, comprising a bar 47 and a block 49, a shutter movably arranged back of said window, a dog or pawl adapted to be brought 35 in engagement with said block 49 for holding said bar in its raised position, and means connected with said resetting device for moving said shutter while raising said bar, substantially as and for the purposes set forth.

46. In a cash-register, the combination, with a casing having a window 9, of a shaft in said casing, a pinion and indicating-drum on said shaft, a drum-actuating means, a resetting device, comprising a bar 47 and a block 45 49, a shutter movably arranged back of said window, a dog or pawl adapted to be brought 50 in engagement with said block 49 for holding said bar in its raised position, and means connected with said resetting device for moving said shutter while raising said bar, consisting, of a frame 120 on said main shaft, a pin on said frame, a pivoted arm 116 having a 55 forked end portion in engagement with said pin, and having its lower end in operative engagement with a portion of said resetting device, and a spring between said frame 120 and said arm 116, substantially as and for the purposes set forth.

47. In a cash-register, adding mechanism, 60 a rotary talking-machine record, an annunciator therefor, a motor for actuating said record, manually-operative means for actuating said adding mechanism to register the amount of a sale and setting the said annunciator in position on the said record with re- 65

spect to such amount, and means for releasing said motor to actuate said record; substantially as set forth.

48. In a cash-register, a set of adding mechanisms, a set of rotary talking-machine records comprising one record for each of said mechanisms, annunciators for said records, spring mechanism for actuating said records, a set of manually-operative independent elements for actuating said adding mechanisms 70 to register the amount of a sale and setting said annunciators in position on the said records with respect to such amount, and means for releasing said spring mechanism to actuate the records; substantially as set forth. 75

49. In a cash-register, an indicator normally concealed, adding mechanism, a rotary talking-machine record, an annunciator therefor, spring mechanism for actuating said record, manually-operative means for 80 setting the indicator, actuating said adding mechanism to register the amount of a sale and setting said annunciator in position on said record with respect to such amount, and means for exposing the indication and releasing 85 said spring mechanism to actuate said record; substantially as set forth.

50. In a cash-register, an indicator normally concealed, adding mechanism, a rotary talking-machine record, an annunciator 90 therefor, spring mechanism for actuating said record, manually-operative means for setting the indicator, actuating said adding mechanism to register the amount of a sale and setting said annunciator in position on 95 said record with respect to such amount, means for exposing the indication and releasing said spring mechanism to actuate said record, and means for concealing the indicator and moving said annunciator to its initial 100 inoperative position preparatory to adding, indicating and announcing the amount of a 105 further sale; substantially as set forth.

51. In a cash-register, a set of adding mechanisms, a set of rotary talking-machine records comprising a record for each of said mechanisms, annunciators for said records, spring mechanism for actuating said records, a normally concealed indicator, a normally locked cash-drawer, a set of manually-operative independent elements for setting the indicator, actuating the adding mechanism to register the amount of a sale and setting the annunciators in position on said records with respect to such amount, and means for exposing the indication, freeing the cash-drawer and releasing said spring mechanism to actuate said records; substantially as set forth. 110 115 120

Signed at New York city, in the county of New York and State of New York, this 23d 125 day of July, A. D. 1904.
